ANGULAR FUNCTION RESISTOR

Kaj Leo Nielsen and Edward H. Roland,
Indianapolis, Ind.

Application May 6, 1952, Serial No. 286,414

8 Claims. (Cl. 201—48)

(Granted under the act of March 3, 1883, as
amended April 30, 1928; 370 O. G. 757)

1

This invention relates to a variable resistor. More specifically, it relates to a resistor that may be varied in accordance with the functions of an angle.

In certain installations such as computers it may be desirable to have the angle of a turning member expressed as a resistance that is proportional to some function such as the sine of the angle. Of course, it is possible to accomplish this by the use of a resistor that is not uniform per unit of length or one that is of non-circular shape.

However, there are certain advantages in employing a circular resistance that is uniform per unit of arcuate length. It is accordingly an object of the present invention to adapt such a uniform circular resistor to expressing a resistance proportional to a function of an angle of a turning member.

Other objects and many of the attendant advantages of this invention will be readily appreciated as the same becomes better understood by reference to the following detailed description when considered in connection with the accompanying drawings wherein:

Fig. 1 is a schematic view of one form of the present invention;

Fig. 2 is a schematic view of a second form; and Fig. 3 is a schematic view of a third form.

Fig. 4 is a schematic view of a fourth form.

Fig. 5 shows a wire-wound resistor card.

Fig. 6 is a face view of an actual embodiment of the device shown in Fig. 1.

Fig. 7 is a sectional view taken on the line 7—7 of Fig. 6.

Fig. 8 is a sectional view taken on the line 8—8 of Fig. 7.

In Fig. 1 the reference character 10 designates a resistor of circular shape with a uniform resistance per unit of arcuate length. The resistor should have an arcuate length of $2B$ degrees. The ends 11 and 12 of the resistor are connected by a shunt 13. An arm member 14 is pivotally mounted at a point 15, which is at the middle of the chord 16 between the ends of the resistor. The pivot point 15 is spaced from the center 17 of the resistor an amount equal to xr , r being the radius of resistor. The arm member 14 is adapted to move along the resistor 10 in electrical contact therewith. The values or ranges of values of the angle B and the displacement xr will be demonstrated.

Applicants have discovered certain optimum values of the displacement xr of the arm pivot and the angle B at which the effective resistance R of the resistor 10 is almost exactly directly proportional to the sine of the angle C . They have also discovered certain upper and lower limits for values of xr and B at which the effective resist-

2

ance will vary no more from the proportionality to the sine of the angle than certain workable percentages, say 5% and 10%.

The effective resistance R of the device measured between the shunted ends of the resistor 10 and the arm is expressed in the following equation in which R_1 is the resistance between the resistor end 11 and the arm 14, and R_2 is one-half the total resistance between ends 11 and 12 for a given angle C of the arm measured from the resistor end 11:

$$R = \frac{R_1(2R_2 - R_1)}{R_1 + 2R_2 - R_1} = R_1 \left(1 - \frac{R_1}{2R_2}\right)$$

15 When C is 90° ,

$$R_1 = R_2$$

and

$$R = R_2 \left(1 - \frac{R_2}{2R_2}\right) = R_2 \left(1 - \frac{1}{2}\right) = \frac{1}{2}R_2$$

20 Since R is approximately proportional to the sine of angle C , the following relation is obtained

$$\begin{aligned} 25 \quad \frac{\sin C}{\sin 90^\circ} &\doteq \frac{R_1 \left(1 - \frac{R_1}{2R_2}\right)}{\frac{1}{2}R_2} \\ &\doteq \frac{R_1}{R_2} \left(2 - \frac{R_1}{R_2}\right) \quad (1) \end{aligned}$$

25 But since R_1 is proportional to $(B - A)$ and R_2 is proportional to A ,

$$\frac{R_1}{R_2} = \frac{B - A}{B}$$

30 Substituting for $\frac{R_1}{R_2}$ in (1)

$$\begin{aligned} 35 \quad \sin C &\doteq \left(\frac{B - A}{B}\right) \left(2 - \frac{B - A}{B}\right) - \\ &\quad \left(\frac{B - A}{B}\right) \left(\frac{B + A}{B}\right) = 1 - \left(\frac{A}{B}\right)^2 \quad (2) \end{aligned}$$

but

$$40 \quad 45 \quad \sin C = \frac{xr + r \cos A}{H} \quad (3)$$

Since H is the hypotenuse of a right triangle having sides $r \sin A$ and $xr + r \cos A$,

$$\begin{aligned} 50 \quad H^2 &= r^2 \sin^2 A + (xr + r \cos A)^2 \\ &= r^2 \sin^2 A + x^2 r^2 + 2xr^2 \cos A + r^2 \cos^2 A \\ &= r^2 (1 + x^2 + 2xr \cos A) \end{aligned}$$

55 Substituting for H in (3),

$$55 \quad \sin C = \frac{xr + r \cos A}{r \sqrt{1 + x^2 + 2xr \cos A}} \quad (4)$$

But

$$60 \quad x = \cos(180 - B) = -\cos B$$

Substituting for x in (4) and dividing numerator and denominator by r ,

$$\sin C = \frac{\cos A - \cos B}{\sqrt{1 + \cos^2 B - 2 \cos A \cos B}} \quad (5) \quad 5$$

Equating (2) and (5)

$$1 - \left(\frac{A}{B}\right)^2 = \frac{\cos A - \cos B}{\sqrt{1 + \cos^2 B - 2 \cos A \cos B}} \quad (6) \quad 10$$

In order to obtain the optimum value of the displacement xr , it is necessary to find the optimum value of the angle B which will most nearly satisfy (6) for all values of A . 15

The best approach to a solution is a method of successive approximations. Solutions for B are obtained for the values of A spaced 10 degrees from one another as indicated in Table I, 20 which follows:

Table I

A	0	10	20	30	40	50	60	70	80	90	100	110
B	all		114.025	113.980	113.938	113.896	113.872	113.862	113.895	113.982	114.146	-----

The arithmetic average value of B is 113.955. The corresponding displacement xr of the arm pivot 15 from the resistor center 17 is

$$r \cos 113.955 = .406019 r$$

Substituting these values in (6), we obtain: 30

$$1 - .252800829 A^2 = \frac{\cos A + .406019020}{1.164851445 + .812038040 \cos A}$$

an expression, the right hand side of which yields the exact value of $\sin C$ and the left hand side of which yields an approximate value of $\sin C$. The deviations for the various values of A and the corresponding values of C are given in the following table: 35

A	C	differences	Percent
0	90	0	0
10	82.8833	.0000034	0
20	75.7399	.0000096	0
30	68.5418	.0000085	0
40	61.2586	-.0000109	0
50	53.8558	-.0000534	0.01
60	46.2929	-.0001087	0.02
70	38.5214	-.0001442	0.02
80	30.4815	-.0001079	0.02
90	22.0981	.0000456	0.01
100	13.2764	.0002754	0.12
110	3.8962	.0002600	0.38
113	.9515	.0000849	0.51
113.5	.4542	.0000425	0.54
113.6	.3545	.0000335	0.54
113.7	.2548	.0000243	0.55
113.8	.1548	.0000149	0.55
113.9	.0550	.0000053	0.56
113.955	0	0	0

From the foregoing, it is seen that a value of $B = 113.955$ and a value of $xr = .406019 r$ are quite satisfactory. Only at very small values of the angle C are the percentage errors appreciable, and the errors inherent in small resistances such as those in wire-wound cards far outweigh the theoretical errors. 45

Further calculations show that as the minimum value of angle C rises, the greater can be the deviation both up and down from the optimum value of $xr = .406019 r$ for a given permissible percentage of error; that as the permissible percentage of error rises the greater can be the deviation both up and down from the optimum value of xr for a given minimum value of angle C ; that as the minimum value of angle C decreases the percentage error increases for a given value of xr . This may be seen from the following tables. 65

Table II

B	x	Minimum C for 5% error	Minimum C for 10% error
90	0	50°	33
95	.0872	43.6	24.5
100	.1737	33.8	13.2
1	.1908	31.4	10.8
2	.2079	29.0	6.9
3	.2250	26.2	3.0
4	.2419	22.9	less than 1
5	.2588	19.2	less than 1
6	.2756	15.4	less than 1
7	.2922	11.6	less than 1
8	.3090	5.9	less than 1
9	.3256	1.0	less than 1
110-120	.34-.50	less than 1	less than 1
121	.5158	2.0	less than 1
22	.5300	8.1	less than 1
3	.5446	11.7	less than 1
4	.5592	14.3	less than 1
5	.5730	16.4	less than 1
6	.5878	18.9	less than 1
7	.6018	22.0	less than 1
8	.6157	2.0	2.0
9	.6293	3.0	3.0
130	.6428	6.2	6.2

Table III

If the sin C is not to be measured for angles less than—	And an approximate 5% error is allowable then the x may be in the interval—	And a 10% error is allowable then the x may be in the interval—
1°	.325 < x < .500	.242 < x < .602
5°	.313 < x < .517	.215 < x < .635
10°	.295 < x < .535	.190 < x < .700
15°	.275 < x < .565	.165 < x < .765
20°	.255 < x < .595	.130 < x < .835
25°	.230 < x < .625	.085 < x < .935
30°	.200 < x < .655	.035 < x < .985
35°	.155 < x < .700	0 < x < 1.00
40°	.120 < x < .750	
50°	0 < x < 1.00	

From Table III it may be seen that for a minimum value of one degree for angle C , variation of x from .325 to .500 will produce no more than 5% error, and a variation of x from .242 to .602 will produce no more than 10% error. 45

Calculations also show that if x is held to $.41 \pm .05$, the percentage error will be about 3.12 at a shade more than one degree for angle C . If angle C is increased, the percentage decreases. 50

The arm pivot 15 is at the midpoint of the chord 16 between the resistor ends 11 and 12 so that the largest value of the effective resistance R which naturally comes when R_1 and R_2 are equal, occurs when the angle C is 90 degrees, at which the sine is of course at a maximum. If the arm member 14 is not to move through an angle as large as 90 degrees, then the arm pivot 15 need not be substantially at the midpoint of the chord 16 between the resistor ends 11 and 12. 55

The resistor 10 may take the form of a wire-wound card bent to arcuate cylindrical shape, the arm 14 contacting the ends of the wire turns at one edge of the card. 60

In Fig. 2 a resistor 18 which has a uniform resistance per unit of arcuate length, has the form of a complete circle, and a shunt 18^a connects two resistor points 19 and 20, which should have a spacing as described with reference to Fig. 1. The pivot 15 of the arm member 14 will be at the midpoint of the chord 16 between the points 19 and 20. The arm pivot 15 will be spaced from the resistor center an amount equal to a fraction 70 of the resistor radius as specified with reference

to Fig. 1. The effective resistance R will be proportional to the sine of the angle A , as in Fig. 1. The resistor 18 may be formed of a wire-wound card bent to a complete circular cylinder, or the resistor may be of circular shape or circular cylindrical shape formed in any other suitable way. Stops 22 and 23 are provided to keep the arm member 14 on the larger angle of the resistor 18 between points 19 and 20.

In Fig. 3 the resistor is formed of two circular sections 24 and 25, each of the arcuate length described with reference to Fig. 1. The sections have the same radius and the same uniform resistance per unit of arcuate length and are connected at their ends in junction points 27 and 28 in opposed facing relation with their centers 29 and 30 on opposite sides of the chord 26 connecting the junction points 27 and 28. The pivot 15 of arm member 14 is at the midpoint of chord 26, spaced from each of centers 29 and 30 an amount equal to a fraction of the radius of the sections as specified with reference to Fig. 1. A shunt 31 connects the junction points. The effective resistance R across the shunt 31 and the arm member will be proportional to the sine of the angle A , as in Figs. 1 and 2. In Fig. 3 the arm member may operate over 360 degrees.

In Fig. 4 the arrangement is the same as in Fig. 1 insofar as arcuate length of the resistor 10, location of arm pivot 15, and use of shunt 13 are concerned. However, in Fig. 4 the arm member is replaced by a member 32, which is in effect a pair of rigidly connected arm members extending in opposite directions from the pivot 15. The member 32 enables the device to operate over 360 degrees as in Fig. 3.

Fig. 5 shows a card 35 wound with an enameled resistance wire 36. The enamel is removed from the wire at the top edge of the card. The ends of the winding are anchored in holes 37 in the card 35, and terminal connector portions 38 project therefrom. As shown in Figures 6 and 7, the card 35 is bent to circular shape about a pot 39, which may be formed of a light-weight metal such as aluminum, and is clamped thereto by flange members 40 riveted to the ends of the card as indicated at 41 and by bolts 42 and nuts 43. Pieces 44 are riveted to the ends of the card on the opposite side to the flange members 40. As seen in Fig. 7, the wire-wound card 35 abuts a shoulder 45 at its left end, and its right end projects beyond the pot 39 and is contacted by a contact block 46, having a triangular section, as seen in Fig. 8. The block is secured by screws 47 to the outer end of an arm 48 of this section.

The inner end of the arm 48 is secured by screws 49 to a semi-circular portion 50 of a collar 51. The collar is clamped to a flanged insulating sleeve 52 on the right end of a shaft 53 by means of lugs 54 on the collar and a screw 55 extending through and into the lugs. The shaft 53 is journaled in a sleeve 56, which is externally threaded to receive clamp nuts 57 and 58 which hold the sleeve in an elongated slot 59 formed in the pot 39. A washer 60 fits between the nut 57 and the pot, and a spacer 61 fits between the nut 58 and the flange on the insulating sleeve 52. The sleeve 56 and the shaft 53 are bodily adjustable transversely of their length in the slot 59 to bring the shaft to an appropriate offset from the center of the resistor card 35. However, if this offset, which is the amount xr previously referred to, is determined, the slot can be replaced by a circular opening.

The collar 51 is in sliding electrical contact with a resilient spiral spring member 62 which is wrapped around the collar and is attached to a flanged base member 63 secured by a screw 64 to an insulator block 65 and terminating in a projecting end portion 66. The insulator block is secured by screw 67 to the pot 39. Insulated conductors 68 and 69 lead from the ends 38 (Fig. 5) of the resistance wire 36 and are connected to a terminal screw 70 on the insulator block 65. Conductors 68 and 69 comprise the shunt 13 of Fig. 1. Stops 71 limit the angular movement of the arm 48 and the contact block 46 to the appropriate angle $2B$, as discussed with reference to Fig. 1. Three openings 72 spaced 120 degrees from one another about the center of the pot are adapted to receive suitable fastening means that support the pot 39 to another object. It will be seen that the device shown in Figs. 6 and 7 is like the one shown in Fig. 1.

Obviously many modifications and variations of the present invention are possible in the light of the above teachings. It is therefore to be understood that within the scope of the appended claims the invention may be practiced otherwise than as specifically described.

The invention described herein may be manufactured and used by or for the Government of the United States of America for governmental purposes without the payment of any royalties thereon or therefor.

We claim:

1. In combination, a circular resistor having an arcuate length greater than 180 and less than 360 degrees and being of equal resistance per unit of arcuate length, means shunting the ends of the resistor and a member angularly movable along the resistor in electrical contact therewith about a pivot located approximately at a midpoint on a straight line connecting the ends of the resistor, the effective resistance across the member and the shunted ends of the resistor being proportional to the sine of the angle subtended by the member and the straight line connecting the ends of the resistor.

2. In combination, a circular resistor having uniform resistance per unit of arcuate length and an arcuate length of about 228 degrees so as to cause the midpoint of a straight line connecting the ends of the resistor to be displaced from the center of the resistor an amount equal to about .406 times the radius of the resistor, means shunting the ends of the resistor, and a member angularly movable along the resistor in electrical contact therewith about a pivot located approximately at said midpoint whereby the effective resistance across the member and the shunted ends of the resistor is proportional to the sine of the angle subtended by the member and the said straight line.

3. In combination, a circular resistor having equal resistance per unit of arcuate length and being shunted across two points spaced more than 180 degrees and a member having a pivot eccentric to the resistor and located at the midpoint of the chord between said two points and being movable in electrical contact with the resistor along the more than 180 degrees between the points.

4. In combination, a circular resistor having uniform resistance per unit of arcuate length and being shunted across two points spaced approximately 218 to 240 degrees, and a member having a pivot spaced from the center of the resistor by approximately .325 to .500 times the radius of

the resistor and located approximately at a middle of the chord between said points, the member being movable in electrical contact with the resistor along the said 218 to 240 degrees so that the sine of the angle between the chord and the member is approximately proportional to the effective resistance across the member and the shunted points of the resistance.

5. In combination, a resistor formed of two circular sections of the same radius and the same arcuate length greater than 180 and less than 360 degrees and the same equal resistance per unit of arcuate length, the sections being connected through their ends in opposed facing relation with their centers on opposite sides of the chord between their ends, a shunt connecting these ends, and an arm movable along the sections in electrical contact therewith on a pivot approximately at a midpoint of the said chord, the effective resistance across the member and the shunt being proportional to the sine of the angle subtended by the member and the said chord.

6. In combination, a resistor formed of two circular sections having the same radius and the same uniform resistance per unit of length and the same arcuate length of about 228 degrees, the sections being connected through their ends in

opposed facing relation with their centers on opposite sides of the chord between their ends an amount equal to about .406 times the radius, and an arm movable along the sections in electrical contact therewith on a pivot approximately at a midpoint of the said chord.

7. The combination specified in claim 1, the member extending in opposite directions from its pivot so as to be capable of contact with the resistor throughout 360 degrees of movement.

8. In combination, a circular resistor having uniform resistance per unit of arcuate length and being shunted across two points spaced approximately 208 to 254 degrees, and a member having a pivot spaced from the center of the resistor by approximately .242 to .602 times the radius of the resistor and located approximately at a middle of the chord between said points, the member being movable in electrical contact with the resistor along the said 208 to 254 degrees so that the sine of the angle between the chord and the member is approximately proportional to the effective resistance across the member and the shunted points of the resistance.
